S. G. WILSON

POLISHING DEVICE

Filed March 5, 1927

Patented July 17, 1928.

1,677,742

UNITED STATES PATENT OFFICE.

STEPHEN G. WILSON, OF PHILADELPHIA, PENNSYLVANIA.

POLISHING DEVICE.

Application filed March 5, 1927. Serial No. 172,990.

One object of this invention is to devise a novel construction of a polishing device wherein the casing and the filler are constructed and secured together in a novel manner.

A further object of this invention is to devise a novel filler having an outer covering which will present an attractive appearance, and an inner strip of cheaper material. The cover and strip are folded from right to left or from side to side. The cover and strip are sewed together and spaced slots are provided between the sewing and the top folded edge. These slots are adapted to receive a locking member to secure the filler within a back support adapted to be received in a casing which latter is adapted to be grasped by the hand of the user.

With the above and other objects in view, as will hereinafter more clearly appear, my invention comprehends a novel brush consisting of a novel construction of a casing, a novel construction of a filler, a novel back support, and a novel locking member cooperating with the filler, back support and casing in a novel manner to secure the parts in assembled condition.

It further comprehends a novel backing for the filler which is adapted to cooperate with the locking member.

It further comprehends a novel brush wherein the locking member and casing cooperate in such a manner that the filler can be moved outwardly from the casing and locked in such position as the filler becomes worn.

Other novel features of construction and advantage will hereinafter more clearly appear in the detailed description and the appended claims.

For the purpose of illustrating the invention, I have shown in the accompanying drawings typical embodiments of it, which, in practice, will give satisfactory and reliable results. It is, however, to be understood that the various instrumentalities of which my invention consists can be variously arranged and organized and my invention is not limited, to the exact arrangement and organization of these instrumentalities as herein set forth and claimed.

Figure 1 is a perspective view of a polishing device embodying my invention.

Figure 2 is a section on line 2-2 of Figure 1.

Figure 3 is an end elevation of the brush. Figure 4 is a section on line 4-4 of Figure 3.

Figure 5 is a perspective view of a backer for the filler.

Figure 6 is a plan view of the blank from which the casing is formed.

Figure 7 is a perspective view of a portion of a locking member.

Figure 8 is a top plan view of a locking member in detached position.

Figure 9 is a perspective view of the filler.

Similar numerals in the drawings indicate corresponding parts.

Referring to the drawings:

The grasping portion of the polishing device is formed from a blank 1 having longitudinally weakened lines 2 at each side, spaced from its marginal edges so as to form the sides 3 when bent downwardly, and these sides are provided with the transversely extending slots 4 which are adapted to receive the tongues 5 of the end extensions 6, which latter extend outwardly beyond the body of the blank and are arranged at each end in pairs.

The diagonally located extensions 6 at opposite ends of the blank are provided with the notches or serrations 7. When the blank is folded, as shown in Figures 1 and 2, it forms a casing and the sides 3 are locked in position by the tongues 5 extending into the slots 4.

8 designates the filler which is formed of an outer strip of fabric 9 which is folded upon itself and between the fold is a strip of material 10 which can be of inexpensive material such as for example, felt. The strips 9 and 10 are then folded together and sewed together, spaced slots are made between the sewing and top folded edge, as will best be understood by reference to Figures 2, 4, and 9, a spring strip 14 is then passed through said slots and the filler is then inserted into a holder 11 which consists of a rectangular box shaped member open at its bottom and provided in its sides and top with apertures 12 which are for ventilation, and having in its ends, slots 13.

The ends of this holder 11 are provided with the slots 13 through which is adapted to pass a locking member 14 of novel construction, said locking member also passing through the slots 15 formed by the end extensions 6. This locking member 14 con-

sists of a flat strip of spring material, preferably metal, the ends of which are deflected in opposite directions, and at the ends they are provided at the top and bottom with the laterally extending inclined flanges 16 which form locking members and are adapted to engage with the juxtaposed notch or serration of the notches or serrations 7. At each end, this locking member 14 has detachably connected therewith a grasping handle 17 preferably in the form of a ring as illustrated. One ring being removed, this locking member 14 passes through slots 18 in the filler. These slots are spaced between the sewing and the top folded edge of the filler.

The filler as an article of manufacture consists of the strips 9 and 10 which are folded from left to right or from right to left so as to form a lapped construction. The locking strip 14 is passed through the slots 18 in the filler and the slots 13 in the back so that the filler is now assembled with respect to its back 11.

This back with the filler and the locking member 14 are then inserted into the casing or grasping portion. The locking member passes through the slots 15 at the end of the casing. As before explained, the locking member 14 has a twist set in it so that the top locking portion 16 will engage one of the notches 7 at the left hand end of the casing, and the top flange 16 at the opposite end of the locking member will engage the juxtaposed notch 7 at the top, at the right hand end of the casing. The lower flanges contacting with the smooth edges of the slot 15 in the extensions 6, contribute to retain the top flanges in locking engagement with the walls of the notches.

After the filler has become worn, the filler and its back, together with the locking member, may be moved outwardly, relatively to its casing, by the operator taking hold of the rings 17 and slightly twisting or turning the ends of the locking member 14 in a direction to disengage the locking flanges from their notches. The locking member, back and filler can then be moved outwardly as a unit of structure to engage an outer notch so that the filler can be made short and stiff, or long and soft, or can be used until it is practically worn out.

The casing may, if desired, be provided with the cut out portions, such as, for example, the cut outs 19 of any desired contour, as seen in Figures 1 and 6, in order to reduce the weight of the brush and provide for ventilation and a better hand hold.

It will be apparent that in accordance with

this invention the filler can be moved outwardly from the casing until it is practically worn out, and when worn out the old filler can be readily removed and a new filler inserted, so that the casing, locking member, and back for the filler can be used for a long period of time, and the filler can be replaced as it becomes necessary.

Having thus described my invention what I claim as new and desire to secure by Letters Patent, is:—

1. A polishing device comprising a casing open at its bottom and having slots and notches at its ends, a filler, a back to receive said filler, and a flat strip of spring material passing through said filler and back and having laterally extending inclined flanges cooperating with said slots and notches to retain said filler and back within said casing.

2. A polishing device comprising a casing open at its bottom and having slots at its ends, the edges of which are provided with vertically disposed notches, an open back adapted to fit into said casing and having slots at its ends, a filler in said back comprising a plurality of folded strips, and a spring locking strip having a twist and having at its ends side flanges to engage desired notches said twist providing a spring tension, said locking member passing through said filler and said back.

3. A filler for brushes comprising an outer strip of material folded upon itself, and an inner strip of material sewed within said fold, said folds having spaced slots between the sewing and their top, and said strips being folded laterally so that the free edges of the strips form the polishing face of the filler.

4. A polishing device comprising a casing open at its bottom and having a slot at each end opening through its bottom edge and having one wall of each slot provided with spaced notches, a back having a slot at each end, a laterally folded filler within said back and having slots in alignment with the end slots in said back, a locking member passing through the end slots in said back and the slots in said filler and slideable into said casing slots and having deflected portions to engage desired notches at the ends of the casing which latter overhangs said filler to stiffen it, whereby when the filler and back are adjusted outwardly of the casing the polishing device will be soft and flexible, and when secured a further distance into the casing the filler is stiffer and less flexible.

STEPHEN G. WILSON.
